A CORPORATION OF NEW YORK.

WEB-FEEDING MECHANISM.

1,273,926.

Specification of Letters Patent. Patented July 30, 1918.

Application filed November 17, 1915. Serial No. 61,898.

To all whom it may concern:

Be it known that I, OSCAR ROESEN, a citizen of the United States, residing at New York city, county of Kings, and State of

5 New York, have invented certain new and useful Improvements in Web-Feeding Mechanism, fully described and represented in the following specification and the accompanying drawings, forming a part of the

10 same.

This invention relates to certain improvements in the rolls or bars employed in web feeding mechanism used for guiding and directing the web through the machine.

15 In this class of mechanism, and particularly mechanism for forwarding and directing webs such as are employed in rotary web printing machines, it is desirable to have the turner bars and forwarding and other rolls 20 over which the paper or other web material is led, and by which it is directed, of such character that little friction will be developed between the web and the roll or bar, so that the web will be easily and accurately 25 directed through the machine and liability to injury reduced to a minimum. It is further desirable, particularly where the machine is handling freshly printed products, such as a freshly printed perfected web, that 30 the printed portion of the web be lifted away from the surface of the roll or bar over which the web travels, so as to avoid smudging of the fresh ink, the web being supported in its travel by its unprinted margin portions.

35 It is the object of the present invention to provide an improved construction, for use in web feeding machines, whereby the friction between the web and the rolls or bars 40 over which it is directed or led, is reduced to a minimum, the construction being such that the friction due to the forward movement of the web is reduced to a minimum and also any friction due to a slight side- 45 wise movement of the web is also likewise reduced.

It is a further object of the invention to provide such a construction in which a product, such as a freshly printed web, may be 50 directed or led through a feeding mecha-

nism, the web being supported on its unprinted portions or margins, so that the friction of the web as it passes over the bar is reduced to a minimum and the printed portions of the web are not in contact with 55 the feeding mechanism.

For a full understanding of the invention, reference may be had to the accompanying drawings, in which—

Figure 1 is a plan view showing the preferred form of the roll or bar employed with a printed web for effecting the desired results;

Fig. 2 is a section taken on the line 2—2 of Fig. 1;

Figs. 3 and 4 are detail sectional views showing various modifications which may be employed, and

Fig. 5 is a top plan view of the cover plate shown in Fig. 4 for retaining the balls in 70 place.

Referring now to the drawings, the invention has been shown in connection with part of a printing machine in which the product to be forwarded is a printed paper web, 75 though it will be understood that the invention is adapted for and may be used in other web feeding machines in which a product other than a printed web is forwarded and directed through the machine. In such web 80 printing machines, the printed web W is forwarded and directed through the machine over various rolls or bars. The web is forwarded by any suitable forwarding mechanism, as rolls R. While the invention may 85 be employed with any of the rolls or bars in the machine, in the particular construction illustrated it has been shown in connection with the turner roll or angle roll marked 1, though it will be understood that 90 the invention is applicable to and may be used if desired with any of the rolls or bars over which the web is led or by which it is directed.

Constructions embodying the invention in 95 its preferred form will include in combination with these rolls antifriction devices which shall act to reduce to a minimum the friction between the paper and the surface of the roll over which the paper travels, 100

these devices being preferably of such character as to reduce both the friction due to the forward travel of the paper, or any friction which may be caused by a slight side-
5 wise movement of the paper owing to the paper being improperly led or directed through the machine, or such sidewise friction due to other reasons. While the particular construction of the antifriction de-
10 vices employed for effecting these results may be varied, in the best constructions these antifriction devices will be in the form of a plurality of balls 2 which are mounted in the roll or bar 1. These balls will be mount-
15 ed in the bar so as to have a free turning movement therein, and, furthermore, will be mounted so that they will project slightly above the surface of the roll or bar with which they are employed.

20 These balls may be variously arranged on the roll or bar. Where the product which is passing through the machine is, as in the present instance, a product which has a freshly printed surface, preferably the balls
25 are arranged as shown in Fig. 1, the balls being arranged on the bar so as to form a projecting surface which will come adjacent the margin or unprinted portion of the paper web as it goes over the bar. As shown in
30 Fig. 1, in which a turner roll is shown, that is, a roll which turns and changes the direction of the travel of the paper, this is effected by providing the roll with a groove cut spirally about the roll. The balls 2 are
35 arranged in this groove, and are loosely held therein in any suitable manner. As shown, for instance, in Fig. 2, a groove 3 is provided with a ball-retaining trough 4 suitably held in position in the groove. With this con-
40 struction the printed surface of the web is kept away from the surface of the roll and is supported at its margin, and the balls act to reduce both the forward friction of the web and any sidewise friction, the balls
45 loosely turning in their groove.

In machines operating to produce printed products, and particularly where the product has dried, and in other machines where unprinted and dried products are being forwarded, it may be desirable to increase the number of balls over the surface of the roll so as to provide a greater anti-friction surface for the paper to travel upon, and such construction is within the scope of the present invention. While the number and arrangement of the balls may be varied, two arrangements are shown in Figs. 3 and 4. In Fig. 3 the roll is shown as provided with a groove 5 having a ball retainer 6, the balls being arranged in the retainer in twos. In Fig. 4 the balls are shown as arranged in threes in a groove 7 in the bar, held in place by a cover plate 8, the balls preferably

being arranged with a cover plate as shown in Fig. 5, that is, with groups of two balls 65 alternating with groups of three balls along the surface of the roll where the paper is to come in contact.

While the invention has been shown and described in relation to a turner bar for web printing machines, it will be understood that it may be used in various other relations in which paper is to be forward and directed through a machine, and while the antifriction devices have been shown as arranged 70 in certain numbers and in certain relations, it will be understood that a wide variation may be made in the arrangement and number of the balls without departing from the invention.

80 What is claimed is:

1. In a web feeding device, the combination with means for forwarding a web of material, of a roll or bar over which the web is led, and devices carried by the roll over 85 which the web passes, said devices forming an antifriction surface conforming to the position of the edges or other unprinted portions of the web in its traveling movement.

2. In a web feeding device, the combination with means for forwarding a web of material, of a roll or bar over which the web is led, and antifriction devices on the roll projecting above the surface thereof and forming an antifriction surface for the web 90 conforming to the position of the edges or other unprinted portions of the web in its traveling movement.

3. In a web feeding device, the combination with web forwarding means, of a roll or bar over which the web is fed, and a plurality of balls loosely mounted on the roll and arranged to project above the surface thereof, said balls forming an antifriction 100 surface for the web to travel over.

4. In a web feeding device, the combination with web forwarding means, of a turner bar over which the web is led, and a plurality of balls on the roll arranged spirally of the roll and projecting above the surface 110 thereof, said balls forming an antifriction surface over which the paper travels on its unprinted margins.

5. In a web feeding mechanism, a roll or bar over which the web travels provided 115 with a plurality of loosely mounted balls arranged to project above the surface of the roll and into the path of the web.

6. In a web feeding mechanism, a turner roll or bar over which the web travels provided with a plurality of balls arranged spirally of the roll and projecting above the surface thereof and into the path of the web.

7. In a web feeding mechanism, a roll or bar over which the web travels having its 125 surface provided with a plurality of balls

arranged in sets and projecting above the surface of the roll and into the path of the web.

8. In a web feeding mechanism, a roll or 5 bar over which the web travels provided with a slot, balls in the slot, and ball retainers allowing the balls to have free turning

movements in the slots, the balls projecting above the surface of the rolls and into the path of the web. 10

In testimony whereof, I have hereunto set my hand.

OSCAR ROESEN.
